STAMPING MACHINE

Arthur M. Wickwire, Jr., Nutley, N. J., assignor to
 Peerless Roll Leaf Co. Inc., Union City, N. J., a
 corporation of New York

Application June 5, 1933, Serial No. 674,383

9 Claims. (Cl. 101—3)

This invention relates to monogram or other small type press or stamping machine.

An object of the invention is the provision of a press of small size, as for the letter types of a monogram, the chase being mounted for ready insertion or substitution of the letter types by movement to a position of convenience for insertion or substitution of the monogram type, the assembly being arranged to effect rigidity of the chase and the thereto connected parts during the stage of impressing.

More specifically, the chase holder is rigidly secured to a plunger which is longitudinally slidably mounted in a vertical frame support, the plunger being operated by a cam or other lever pivotally mounted upon the vertical frame support and guided by pin and slot connection thereby, the plunger being normally held within its vertical frame support by suitable spring means, such as a retractile coil spring or preferably a pair of such springs at each side. The spring means enable the plunger to be reciprocated and retained in type setting position, in which movement the plunger swings upon its pins within their slots.

A feature of the invention is the employment of a single element represented by the above referred to plunger, to which the chase holder is rigidly secured and which single element is operated by the manipulated cam or other lever.

A feature of the invention is the assembly of such single element represented by the above referred to plunger, disposed in a frame presenting a guideway in which the single element is reciprocated, a connection affording pivotal movement of such single element relative to the frame and resilient means serving partially to retain the single element in its reciprocation in such guideway, to effect the return of the single element in its return movement and to hold the single element and therewith the chase holder in stable position when the chase holder is moved to tight setting position.

Further features and objects of the invention will be more fully understood from the following detail description and the accompanying drawing, in which

Fig. 1 is a side elevation, partly broken away in vertical section, of a stamping machine embodying my invention; the dot and dash position of the plunger and thereon supported chase indicates the position for insertion of the type;

Fig. 2 is a front elevation of Fig. 1, a part of the take-up reel being broken away.

55 Referring to the drawing, the frame 10 is suit-

ably secured to the base 11. The chase 12 is suitably permanently or otherwise rigidly secured to the end of the plunger 13. The plunger 13 is received within the vertical guideway 14 having solid edge members 15, 15, formed on the front 60 face of the frame 10.

The frame 10 is designedly of solid construction, to have ample weight and sufficient safety factors; the plunger is of ample dimensions to insure positive operation.

The plunger 13 is reciprocally mounted within the guideway 14 by means of the upwardly disposed, oppositely projecting pins 16, 16, received within the respective vertically extending slots 17, 17, supplemented by suitable spring means 18, serving to normally hold the plunger upwardly and inwardly relative to the guideway 14, and the pins 19, 19, coacting with the spring means and also with the plunger in its movement in the guideway.

Such spring means is advantageously in the form of individual oppositely disposed retractile coil springs 18, 18, respectively extending from the pins 19, 19, which are secured to and extending laterally of the plunger 13, and the spring 70 anchoring pins 20, 20, secured to the frame 10. Preferably, the positions of the pins 20 are related to the pins 16 to tension the plunger 13 toward and upwardly within the inner face of its guideway 14 in the frame 10, and to be eccentric 75 relative to the positions of the pins 19 and the pins 16 when the plunger 13 and the chase 12 are moved to type setting position.

The plunger 13 is operated by any suitable means. A convenient operating means is in the form of a cam lever comprising the cam element 21 secured to or integral with operating arm 22, the free end of which is provided with a hand-piece 23. The arm 22 is shown pivoted at 23a to the frame 10.

The stamping machine is advantageously operated with embossing media, and for this purpose I provide a ribbon 24 of suitable embossing material, such as regulation so-called roll leaf, that is, a strip of paper serving as the carrier, on a face of which is a layer of unctuous or other heat releasing material, upon which is deposited the embossing medium proper, such as genuine gold leaf, comminuted metal leaf in imitation of genuine leaf, such as various brass alloys, or aluminum alloys in imitation of silver and other genuine metal media. The embossing medium may be in the form of "colors" deposited upon the unctuous, i.e. heat releasing layer. The outer face of the metallic or "color" medium is preferably 105 110

sized. For such form of embossing the chase 12 is provided with suitable heating means, such as an electric resistance coil, indicated diagrammatically at 25, to which the cord 26 is connected. 5 Desirably, a thermostat indicated diagrammatically at 27, is included in the circuit of the electric resistance coil 25, to ensure substantially uniform heating, and avoid excessive heating. The cord 26 passes freely through the slot 10a formed 10 within the frame 10 and is of sufficient length to permit the plunger 13 to be moved to its type setting position. Monogram or other type is indicated at 28.

The indicated embossing ribbon may be fed 15 from the reel 28 to the take-up reel 29 by any suitable means, as by a ratchet and pawl take-up mechanism, viz., a ratchet wheel 30, pawl 31, the latter operated by the lever 32 on which it is pivotally mounted and tensioned by its biasing 20 spring 33, the lever 32 being provided with the pin 34 which is normally received within the recess 35, disposed in the rear of the chase holder 12, whereby upon upward movement of the plunger 13, the ratchet wheel 30 is operated to cause a 25 predetermined amount of the ribbon 24 to be fed.

The ribbon 24 is shown passing about the guide pins 36, 36, disposed on opposite sides of the chase 12, the pins 36, 36 being in substantially 30 horizontal relationship and at a level below the maximum vertical movement of the type 28, whereby the used ribbon portion is readily 35 stripped from the stationery or other material stamped.

The spring pressed pawl 37 and its indicated 35 associated ratchet wheel serve as holding means for the reel 29 during the stage of return movement of the feeding pawl 31, and otherwise for preventing the reel 29 from reverse rotation.

The embodiment illustrated in the drawing is 40 particularly designed for effective operation by persons relatively unskilled in the technical art of printing, such as by sales people in department stores, stationery stores, drug stores, and the like, where writing paper, envelopes, and the like 45 are for sale.

My stamping machine enables monograms and other relatively brief printed matter to be impressed conveniently and with great rapidity. 50 Auxiliary devices, such as the guide pins 40 and co-ordinately spaced vertical recesses 41 are provided for properly registering the material to be impressed relative to the monogram or other type 28.

The oppositely disposed spring fingers 42 serve 55 to limit the upward movement of the material impressed succeeding the stamping operation; that is to say, in impressing material with heat releasable embossing and other impression medium, the type characters 28 in the chase 12 are 60 heated by the heating coil 25, and upon downward movement of the plunger 13 the type engage the paper side of the impression strip 24, the type and the engaged ribbon portion 24, continuing in such downward movement until contact 65 is made by the sized face of the ribbon 24 upon the material to be stamped. Accordingly, the unctuous material and underlying metallic or "color" layers are heated and released from the paper carrier upon the material impressed, 70 accurately conforming to the contours of the type 28, the unctuous material after cooling serving as a sizing for the deposited metallic or "color" impression.

75 In like manner, leather, fabrics, and other suit-

able material may be embossed or otherwise stamped.

From the above, it is apparent that my invention provides for a base, a vertically extending arm rigidly secured to the base, the arm being provided with a slot extending to a vertical face of the arm to afford a guideway, a plunger vertically reciprocated in the quickway, the plunger being mounted in the guideway by pin and slot connection, the last-named slot extending substantially vertically, and pins carried by the plunger at its portion thereof extending beyond the guideway and adapted to ride upon the facial areas of the guideway in the vertical reciprocation of the plunger, and coil springs secured to such pins tending to normally hold the plunger within the guideway and upwardly toward non-impressing position.

Such pin and slot mounting means of the plunger and such coil spring means preferably serve 95 also to hold the plunger stable when moved to type inserting position.

By the provision of the slot in the arm, the electric cable or wiring connected with the electric heating coil, mounted in or upon the chase, 100 is readily accommodated, and also retracted and protected within the slot during the stage of impressing.

It is observed that the cam 21 serves as a stop for limiting the movement of the plunger 13 and therewith of the chase 12 under the action of the springs 18 to type inserting or changing position.

From the above, it appears that a feature of my invention is the employment of a single element to which the chase holder is rigidly secured 110 and which single element is operated by the manipulated cam or other lever.

The above sets forth as a feature of my invention the assembly of a single element disposed in a frame presenting a vertically extended guideway in which the single element is reciprocated, the pin and slot connection affording pivotal relationship of such single element relative to the frame and cooperating with suitable means represented by the retractile coil springs associated 120 with pins carried by the single element, such retractile coil springs or equivalent serving in coaction with the pins to retain and positively guide the single element in its reciprocation in the guideway, both in its impression movement under 125 actuation of the manipulated means and in its return movement, and further serving in coaction with the pin and slot connection to facilitate movement of the single element and the therewith carried chase holder to type setting or changing 130 position and to hold the single element and the chase holder in stable position in type setting or changing position.

Whereas I have described my invention by reference to specific forms thereof, it will be understood that many changes and modifications may be made without departing from the spirit of the invention.

I claim:

1. In a press, the combination of a base, a frame 140 mounted on the base, the frame presenting a vertically extending guideway wholly open at one side, a rigid plunger normally mounted in the guideway, chase means rigidly carried by the plunger, means for forcibly displacing the plunger 145 longitudinally of the guideway and therewith the chase means to its impressing position, and tension means tending normally to bias the plunger in a direction transverse to the direction of length of the guideway whereby to return the plunger 150

- within the guideway and to hold the plunger in its non-impressing position.
2. In a press, the combination of a base, a frame mounted on the base, the frame presenting a vertically extending guideway wholly open at one side, a single plunger normally mounted in the guideway, chase means rigidly carried by the plunger, means for forcibly displacing the plunger longitudinally of the guideway and therewith the chase means to its impressing position, and tension means exerting a force transversely of the direction of length of the guideway tending normally to hold the plunger in its non-impressing position and to return the plunger within the guideway from its impressing position.
3. In a press, the combination of a base, a frame mounted on the base, the frame presenting a vertically extending guideway wholly open at one side, a plunger normally mounted in the guideway, pins carried by the plunger, said pins slidably engaging fixed open faces carried by the frame, chase means rigidly carried by the plunger, means for forcibly displacing the plunger and therewith the chase means to its impressing position, and spring means connected with said pins for exerting a force transverse of the direction of length of the guideway for returning the plunger from its impressing position, for normally retaining the plunger in the guideway and for holding the plunger in its non-impressing position.
4. In a press, the combination of a base, a frame mounted on the base, the frame presenting a vertically extending guideway wholly open at one side, a plunger normally mounted in the guideway, pin and slot means for movably locating the upper end of said plunger, chase means rigidly carried by the plunger, means for forcibly displacing the plunger and therewith the chase means to its impressing position, and tension means for normally retaining the plunger in the guideway in its normal reciprocation therein and for biasing the plunger in stable position when the plunger and therewith the chase means are moved out of the guideway to type setting position.
5. In a press, the combination of a base, a frame mounted on the base, the frame presenting a vertically extending guideway wholly open at one side, a plunger normally mounted in the guideway, pin and slot means for movably locating the upper end of said plunger, pins carried by the plunger, said pins slidably engaging open faces carried by the frame, chase means rigidly carried by the plunger, means for forcibly displacing the plunger and therewith the chase means to its impressing position, and spring means connected with said pins for normally retaining the plunger in its reciprocation in the guideway.
6. In a press, the combination with a base, a frame provided with a vertically extending slot serving as a guideway wholly open at one side, a plunger dimensioned to be closely received within the facial portion of the slot, pin means carried by said plunger, said frame being provided with slot means extending substantially parallel to the guideway, said slot means receiving said pin means and coacting therewith to movably position the upper end of the plunger said plunger having a portion extending beyond said guideway and provided with pin means coacting with front facial portions of the frame, resilient means secured to said second-named pin means for exerting a force transverse to the direction of length of the guideway, chase means rigidly carried at one end of the plunger, and cam means for operating the plunger.
7. In a press, the combination with a base, a frame provided with a slot extending to a vertical front face of the frame to serve thereat as a guideway, a plunger dimensioned to be closely received within the facial portion of the guideway, pin means carried by said plunger, said frame being provided with slot means extending substantially parallel to the facial portion of the guideway, said slot means receiving said pin means and coacting therewith to movably position the upper end of the plunger the plunger having a portion extending beyond the guideway and provided with pin means coacting with front facial edge portions of the frame, resilient means secured to said second-named pin means for exerting a force transverse to the direction of length of the guideway, chase means rigidly carried by the lower end of said plunger, and cam means for operating said plunger by engagement with an upper portion of the plunger.
8. In a press, the combination of a base, a frame mounted on the base, the frame presenting a guideway wholly open at one side, a movable plunger normally mounted in the guideway, chase means carried by the plunger, means for forcibly displacing the plunger and therewith the chase means to its impressing position, and tension means connected to the plunger for exerting a force transverse of the direction of length of the guideway for normally retaining the plunger in the guideway and for holding the plunger and therewith the chase means in its non-impressing position.
9. In a press, the combination of a base, a frame mounted on the base, the frame presenting a guideway wholly open at one side, a movable plunger normally mounted in the guideway, pin and slot means for connecting an upper part of the plunger relative to the frame, chase means carried by the plunger, means for forcibly displacing the plunger and therewith the chase means to its impressing position, and tension means connected to the plunger for exerting a force transverse of the direction of length of the guideway for normally retaining the plunger in the guideway and for holding the plunger and therewith the chase means in its non-impressing position, the connection of said tension means with the plunger and the chase means being related to the aforesaid connection of the upper part of the plunger to bias the plunger in stable position when the plunger and therewith the chase means are moved out of the guideway to type setting position.

ARTHUR M. WICKWIRE, JR.
